TUNING CONTROL FOR RADIO RECEIVERS
OR THE LIKE

Mahlon W. Kenney, Oak Park, and Andrew A. Gedde, Chicago, Ill.

Application May 24, 1937, Serial No. 144,387

6 Claims. (Cl. 250—20)

This invention relates to a device for tuning a radio receiver or the like.

In so-called "automatic" tuning devices for tuning a radio according to the call letters of a desired broadcast station, the individual controls must be initially preset or adjusted in their relations to the tuning element so that each control will thereafter move the tuning element to the proper position required to tune the receiver to a particular selected station. This presetting or adjusting operation is complex in character because of the complexity of the mechanism and requires for its performance partial disassembly of the control mechanism. Accordingly, the practice has arisen of having a factory or sales representative make the original adjustment after ascertaining from the prospective user the stations which he customarily selects. If later the tuning position for one or more of these selected stations varies, as it almost universally does, or if it is desired to change from one automatically selectable station to another, the mechanism must be disassembled, adjusted and reassembled. This requires for satisfactory performance the services of a radio technician or service man and results in considerable expense.

Furthermore, in such present automatic devices the adjustment permitted is only rough in character, reliance being had to a large extent upon the functioning of the automatic frequency control to bring the receiver frequency in step with the carrier frequency. The adjustment of the control to select stations whose carrier frequency is close to that of a local, high power station is therefore made impossible.

It is accordingly an object of applicant's invention to provide an "automatic" tuning control which shall include simple and readily manipulatable presetting means for adjusting the control properly to select the desired stations.

Another object is to make such adjustable means accessible and operable without disassembly of any part or portion of the automatic control, and specifically to provide means permitting presetting of the automatic control from the front of the operating mechanism.

A further object is to provide efficient and sensitive means for precisely adjusting or presetting automatic tuning controls for radio receivers or the like.

A further, more specific object of the invention is to provide in a selective adjusting mechanism of the type disclosed in applicant's copending application, Serial No. 100,156, filed September 10, 1936, improved means for presetting and adjusting the mechanism properly to select the desired stations.

A further object is to provide an automatic tuning device of a simple, compact and efficient construction capable of ready adjustment to effect

a change in the stations automatically selectable by operation of the device.

Other objects and advantages of the present invention will more fully appear from the following detailed description, which, taken in connection with the accompanying drawings, will disclose to those skilled in the art the construction and operation of a preferred form of the present invention.

Fig. 1 is a front view of a tuning device embodying the invention. 10

Fig. 2 is a vertical section taken on the line 2—2 of Fig. 1.

Fig. 3 is a vertical section taken along the line 3—3 of Fig. 2.

Fig. 4 is a fragmentary vertical section taken along the line 4—4 of Fig. 2. 15

Fig. 5 is an enlarged fragmentary vertical section taken along the line 5—5 of Fig. 2.

Fig. 6 is a vertical section taken along the line 6—6 of Fig. 2. 20

Fig. 7 is an horizontal section taken along the line 7—7 of Fig. 6.

Fig. 8 is a fragmentary view of exploded perspective of certain parts of the mechanism.

Fig. 9 is a fragmentary enlarged vertical section similar to Fig. 2 and showing a different position of operation of said mechanism. 25

Fig. 10 is an horizontal section taken along the line 10—10 of Fig. 9.

Fig. 11 is a view similar to Fig. 10 with the parts in a different position of operation. 30

Fig. 12 is a schematic illustration of the control circuit embodied in the invention.

As shown in the drawings, applicant's invention embodies a supporting frame or casting 2 (Fig. 8), substantially in the form of a disk having an annular guide portion 4 and a recessed body portion 6. The body portion 6 is provided centrally with a rearwardly extending, circular housing or boss 8 and a radially extending offset portion 10 communicating with the portion 8 and forming therewith a housing for elements later to be described.

The casting 2 is provided with reinforcing webs 12 (Figs. 2 and 6) extending radially from the portion 8 and adjacent thereto these webs are provided with bosses 14, the bosses 14 being threaded to receive screws 16 for attaching to the casting 2 a rear cover plate or housing 18. A slot 20 is cut in the lower edge of the casting 2 in radial alignment with the center of the housing formed by the portions 8 and 10, and this slot communicates with a slot 22 formed in the guide portion 4 of the casting 2. As will be seen in Fig. 8, the slot provides a pair of lips 24 of less height 40

50 and partially closing the slot 20.

The lower part of the rear wall of the offset portion 10 is cut away to expose a set of four contacts 26, 28, 30 and 32 (Figs. 2, 6 and 8 to 12) which are mounted upon an insulating block 34 55

60

secured to the rear wall of the portion 10 in any convenient manner. Within the rearwardly extending boss or portion 8, there is mounted a stationary axle or bushing 36 (Figs. 2, 4 and 6) which passes through an aperture in the rear wall and is secured in any convenient manner to said wall. The bushing 36 is provided with an enlarged opening 40 extending inwardly from one end to receive a lamp socket 42 and a lamp 44; 10 a lamp cable 46 passing through a central opening 48 in the bushing 36.

A control wheel or gear 50 (Figs. 2 to 5, 8 and 9) is rotatably mounted by its hub portion 52 on the bushing 36 to which it is secured against longitudinal movement by the rear wall of the portion 8 of the casting 2 and by a collar 54 secured to the outer end of the bushing 36 by a set screw 56. The collar 54 is provided with forwardly extending radial arms 58 upon which is mounted a ring 60 to which is secured a transparent or translucent disk 62 carrying the usual indicia representative of radio broadcast frequencies.

A cover member 64 (Fig. 2) is secured to the wheel 50 for rotation therewith by a plurality of screws 66 threaded into the outer ends of pedestals 68 (Figs. 2 and 3) formed integrally with and projecting forwardly from the wheel 50. The cover member 64 is provided with a central opening 70 for receiving the customary glass or crystal 72, through which the dial plate 62 is visible. The cover member 64 is further provided with a plurality of annularly arranged, finger-receiving openings 74 (Figs. 1, 2 and 9) and an index or pointer 76 cooperating with the dial plate 62. A front cover member 78 is spring pressed over the rear cover member 18 at their meeting edges and is provided with an inturned, annular flange 80 (Fig. 2) cooperating with an outwardly extending annular flange 82 and the periphery of the cover member 64 to seal the enclosed mechanism. The cover member 64 is provided with a rearwardly extending annular flange 84 slotted at equally spaced points in alignment with the centers of the openings 74 to form guideways 86 for a purpose later to be described.

The wheel 50 is provided on its rear surface with an annular series of integrally formed ratchets 88 (Figs. 2, 4, 5 and 8 to 11). An opening 90 extends through each of the ratchets and the body of the wheel 50 for the purpose of slidably receiving the pin 92 of a dog 94 which carries a pawl 96 provided with teeth 98 for cooperation with the teeth 100 of its associated ratchet 88. The teeth 100 of each ratchet 88 are formed concentrically to the opening 90 and, like the teeth 98, are in the form of isosceles triangles to prevent rotational movement but to permit longitudinal movement of the dog relative to the ratchet. Each dog 94 is apertured as at 102 to receive the shank 104 of a push button 106 (Figs. 2, 8, 9 and 12) which is secured thereto by a slotted spring clip or collar 108 frictionally engaging in a groove formed on the outer end of the shank 104 and engaging the outer surface of the pin 92. Axial movement of the dog 94 relative to the push button 106 is prevented by the collar 108 and by the engagement of the inner end of the pin 92 with a collar 110 formed by an enlarged portion 112 of the push button 106. Each push button 106 carries a cup-like member 114 having a lip 116 of slightly greater diameter to form a shoulder 118 for supporting a translucent or transparent marking disk 120, 75 upon which is inscribed the call letters of a par-

ticular broadcast station. The push buttons 106 are in number equal to the number of finger-receiving openings 74 and the ratchets 88; in the drawings fourteen such push buttons, openings and ratchets have been shown, although it will be apparent that any number may be provided depending upon the size of the device.

The lip 116 of each push button 106 when in its forward position, is received within an opening 74, and the push button is guided in its rearward movements by a pin 122 formed integrally therewith and slidably received in a slot 86 formed in the flange 84 of the cover member 64.

Each push button is normally urged to its forward position by a spring 124 which surrounds a boss 126 through which the opening 90 extends and the forward movement of the push button is limited by an annular flange 128 formed on the cup-like member 114 adjacent the lip 116. The upper or inner halves of the cup-like members 114 are cut away to permit rays of light from the lamp 44 to pass into the cup member and be reflected by the inner reflecting surface of the cup member to illuminate the marking disk 120.

A toothed contact disk 130 (Figs. 2, 4, 8, 9 and 12) is mounted on an insulating disk 132 secured by studs 134 and springs 136 to bosses 138 formed in the wheel 50 and extending rearwardly therefrom. The teeth of the contact disk 130 are aligned with the push buttons 106 so that, upon rearward movement of the push buttons the shank 104 will contact the teeth of the disk and complete a circuit through the push button and the wheel 50 to the grounded frame 2. The studs 134 and springs 136 permit movement of the contact strip 130 and insulating disk 132 rearwardly relative to the wheel 50, as seen in Fig. 9, the springs 136 normally holding the disk 132 in its forward position in engagement with the bosses 138 (Fig. 2). Ribs 140 (Figs. 2 and 3), extending radially from the bosses 138, provide reinforcement for the wheel 50. A spring contact strip or blade 142 (Figs. 2, 6 and 12) is secured to the recessed portion 6 of the frame casting 2 by the usual insulating strips and by insulated contact bolts 144 which pass through the portion 6 and carry on their outer ends any usual means for receiving and securing an electric conductor thereto.

Each dog 94 is provided with a rearwardly extending pin 146 (Figs. 2, 5 and 8 to 12) which, upon movement of the push button 106, engages an upstanding lug 148 carried by a pivoted stop member 150. The stop member 150 is pivoted by a pin 152 to a bracket 154 carried between a pair of brackets 156 and 158 formed integrally with and depending from the frame 2. The upstanding lug 148 of the stop member 150 is provided with a right-angle, rearwardly extending leg 160 which overlies the lips 24 and is centered with respect to the slot 22; the leg 160 being adapted to engage the edges of the slot 20 to limit the rotation of the stop member 150. An arcuate cam 162 is formed integrally with the stop member 150 and extends rearwardly therefrom, the rear surface 164 being in the form of a shallow V, and operatively engaging a cam roller 166 pivoted in a bracket 168 carried by the contact 30. The pin 146, carried by the dog 94, is adapted under certain circumstances to pass through the slot 22 between the lips 24 and operatively engage an U-shaped bracket 170 affixed to the lower end of the contact member 28.

The brackets 156 and 158 carry bosses 172 and 75

174 which form bushings for shafts 176 and 178. The shafts 176 and 178 extend through the front cover member 78 and carry on their outer ends manually operable knobs 180 and 182, respectively, the shaft 178 having secured thereto intermediately the boss 174 and the cover 78, a gear for meshing engagement with the gear teeth on the wheel 50. Flexible cables 186 and 188 are coupled to the shafts 176 and 178, cable 186 being connected to the volume control (not shown) and the cable 188 being connected to the tuning element or condenser 189 of a remotely located radio receiver (not shown), the coupling between the shafts 176 and 178 and the tuning and volume control shafts of the radio receiver being any of the usual well known forms.

The rear cover member or plate 18 may be additionally secured to the frame or casting 2 by screws 190 threaded in the radially extending openings 192 as shown in Fig. 6, and the entire mechanism may be supported upon the steering column or tube of an automobile by a pair of adjustable brackets 194 bolted to the rear cover member 18. The cover member 18 and the frame 2 may be grounded by the bracket 194 or a separate grounding conductor may be provided, as desired.

In Fig. 12 there is schematically shown the circuit for the contacts 26 to 32 and for the contact disk 130. A number of push buttons 106, which cooperate with the contacts 28 to 32 and the contact disk 130 to complete certain circuits, are schematically represented in Fig. 12 as being grounded, this ground connection being effected through the wheel 50 and the grounded frame or casting 2. The switch contact 26 is connected by a wire 196 to the conventional silencing circuit by which the speaker, or some other portion of the radio receiver, is rendered inoperative to transmit signals whenever the supply lead is grounded during the operation of the automatic tuning control. The switch contact 28 is connected by a wire 198 to the spring contact strip or blade 142 which is in engagement with the contact disk 130. The switch contact 30 is provided with no external connection but is adapted to be connected by the stop member 150 and one of the dogs 94 to a grounded push button 106. The switch contact 32 is connected by a wire 200 to the automatic frequency control circuit of the radio receiver, this automatic frequency control circuit being conventionally rendered inoperative by grounding the normally ungrounded supply lead. It is this normally ungrounded supply lead which is connected to the wire 200.

The bracket 154, upon which the stop member 150 is pivoted, carries at its outer end a V-shaped bracket or plate 202, upon which is supported a pair of conventional control switches 204 and 206, the operating members of which extend through the front cover member 78 and are employed in the conventional manner to energize and control the radio receiver.

The operation of the above described mechanism is as follows: The operator inserts a finger through one of the finger-receiving openings 74 and pushes the associated push button 106 rearwardly into engagement with the contact disk 130 to ground the lead 196 and silence the receiver during the tuning operation, the rearward movement of the push button 106 being limited by the engagement of the pin 146 with the surface of the guide portion 4 of the frame 2. The operator then rotates the cover member 64

and attached wheel 50 in either a clockwise or counterclockwise direction as he may desire. When the operated push button has been moved to its lowermost position, the pin 146 will engage the lug 148 of the stop member 150, the cam 162 of which moves the cam roller 166 rearwardly to cause the contact 30 to engage the contact 32, thus grounding the lead 200 from the automatic frequency control circuit. This grounding of the automatic frequency control circuit renders it inoperative and prevents powerful local stations from interfering with the tuning of the receiver to the desired station. The stop member 150, in being rotated in a clockwise or counterclockwise direction, as the case may be, moves a distance sufficient to permit the pin 146 to aline itself with the slot 22 between the lips 24 of the casting 2, and this movement of the member 150 is limited by engagement of the leg 160 with a side of the slot 20 to a distance equal to one-half the sum of the widths of the slot 22 and the leg 160. This controlled movement of the stop member 150 in either direction assures the identical positioning of the wheel 50 regardless of the direction in which the cover member 64 is rotated. The rotation of the gear 50 is transmitted by the gear 184 to the tuning shaft 178 and by the tuning cable 188 to the tuning element 189.

In order to preset a push button to a particular station, or to change an adjustment previously made, the control knob 182 is operated to rotate, through the gear 184, the wheel 50 and cover member 64 to the approximate tuning position for the desired station, according to the wave length indicated on the dial plate 62. The push button 106, which is nearest the lowermost position, is then pushed rearwardly and the cover member 64 rotated until stopped by the engagement of the leg 160 of the stop member 150 with the side of the slot 20, the stop member 150 being rotated by engagement of the pin 146 with the lug 148 until the pin 146 is alined with the slot 22. The push button 106 is then pushed rearwardly farther, the pin 146 moving into the slot 22 where it engages and moves rearwardly the contact member 28 to break the connection between the leads 196 and 198 and thereby render the silencing circuit inoperative.

The movement of the dog 94 which causes the pin 146 to move into the slot 22 also causes the teeth 98 of the pawl 96 to disengage the teeth 100 of the ratchet 88 and the wheel 50 is now free to rotate relative to the dog 94, this rotational movement being limited by pins 208 which extend rearwardly from between the adjacent pairs of ratchets 88. When the silencing circuit has been rendered inoperative, by breaking the connection between the contacts 26 and 28, the manually operable knob 182 is rotated slightly in the proper direction sharply to tune the receiver to the particular, desired station. The tuning having been accomplished, the push button 106 is released and is returned by the spring 124 into its original position, the dog 94 assuming a new fixed position relative to the ratchet 88.

A small marking disk 120, carrying the call letters of the station to which the receiver has thus been tuned, is now inserted into the button 106 and is illuminated by rays of light from the lamp 44. Thereafter, whenever this particular push button 106 is depressed and rotated with the cover member 64 until stopped by the stop

member 150, the receiver will be tuned exactly to that particular station.

It will be seen from the above description that applicant has provided a simple, efficient and readily operable means for presetting and adjusting an automatic tuning control mechanism without disassembly of any part or portion of the automatic control, and specifically has provided means operable by the selectively operable push buttons of the automatic control mechanism for presetting and adjusting said mechanism from the front thereof.

It is thought that the invention and numerous of its attendant advantages will be understood from the foregoing description and it is obvious that numerous changes may be made in the form, construction and arrangement of the several parts without departing from the spirit or scope of the invention, or sacrificing any of its attendant advantages, the form herein described being a preferred embodiment for the purpose of illustrating the invention, and the right is hereby reserved to make all such changes as fairly fall within the scope of the following claims.

The invention is hereby claimed as follows:

1. In a tuning mechanism for radio receivers or the like comprising a tuning element, the combination of shiftable means for operating said tuning element, selector means for shifting said first means to predetermined positions whereby to tune the receiver to selected broadcast stations, means operable by said selector means for silencing the receiver during operation of said selector means and said shiftable means, releasable means connecting said selector means to said shiftable means for permitting relative adjustment of said shiftable means and said selector means thereby to vary the positions to which said shiftable means and said tuning element are movable by said selector means and means operable by said releasable means for rendering said receiver operative during relative adjustment of said selector means and said shiftable means.

2. In a tuning mechanism for radio receivers or the like comprising a tuning element and an automatic frequency control circuit, the combination of shiftable means for operating said tuning element, selector means for shifting said first means to predetermined selected positions whereby to tune the receiver to predetermined broadcast stations, releasable means connecting said last means to said shiftable means and operable by said selector means for permitting relative adjustment of said shiftable means and said selector means thereby to vary the positions to which said shiftable means and said tuning element are movable by said selector means, and means operable by said releasable means for rendering said automatic frequency control circuit inoperative during relative adjustment of said selector means and said shiftable means.

3. Selective adjusting mechanism for radio receivers and the like comprising a manually shiftable element, and selective means operable during and as a part of the shifting of said element to stop the same when the desired adjusted position is reached, said selective means comprising a plurality of selectors and a plurality of stop elements having means for connecting said selectors to said shiftable element, said connecting means being releasable from said shiftable element upon operation of said selectors to adjust the stop elements relative to the shiftable element and thereby to predetermine the positions to which said last element is moved by said selectors, said

manually shiftable element comprising a wheel rotatable on an axle, means forming a stationary indicator dial, index means carried by said wheel in position to cooperate with said dial for indicating the adjusted positoin of said wheel, means for supporting a lamp on said axle in position behind said indicating dial to illuminate the same, said selectors comprising depressible buttons, and indicia means on said buttons for indicating the adjusted position of the mechanism controlled by the selectors, said buttons being formed and supported in position to be illuminated by said axle supported lamp.

4. In a tuning mechanism for radio receivers or the like comprising a tuning element, the combination of shiftable means for operating said tuning element, means for silencing the receiver during operation of said tuning element, a plurality of selector means for shifting said shiftable means, a fixed stop member, means associated with each of said plurality of selector means and cooperating with said stop member for stopping said shiftable means in different positions, locking means operable to a released position by each of said plurality of selector means for permitting adjustment of said stopping means relative to said shiftable means by manual operation of said shiftable means thereby to predetermine the positions to which said shiftable means is movable by said selector means, and means responsive to the release of said locking means to render said receiver operative during relative adjustment of said stopping means and said shiftable means.

5. In a tuning mechanism for radio receivers and the like comprising a tuning element, a tuning shaft for operating said tuning element, a plurality of selector means for controlling operation of said tuning shaft to stop said tuning element in predetermined selected positions, said selector means being individually adjustable relative to said tuning shaft to predetermine the selected positions in accordance with the desired broadcasting stations, means for maintaining each of the plurality of selector means in adjusted position, means for silencing the receiver during each tuning operation, means for releasing said maintaining means to permit adjustment of its associated selector relative to the tuning shaft, and means responsive to the operation of said releasing means for rendering said receiver operative during relative adjustment of said selector means and said tuning shaft.

6. In a tuning mechanism for radio receivers and the like comprising a tuning element, the combination of shiftable means for operating said tuning element, selector means for shifting said first means to predetermined positions whereby to tune the receiver to selected broadcasting stations, a silencing circuit selectively controlled by said selector means for silencing the receiver during operation of said selector means and said shiftable means, releasable means connecting said selector means to said shiftable means for permitting relative adjustment of said shiftable means and said selector means thereby to vary the positions to which said shiftable means and said tuning element are movable by said selector means, and switch means operable by said releasable means for breaking said silencing circuit to render said receiver operative during relative adjustment of said selector means and said shiftable means.
